MACHINE FOR OPERATING UPON THE
SOLES OF SHOESJohn L. Jones, Weymouth, Mass., assignor to
United Shoe Machinery Corporation, Paterson,
N. J., a corporation of New Jersey

Application May 10, 1933, Serial No. 670,321

21 Claims. (Cl. 12—18)

This invention relates to improvements in machines for operating upon the soles of shoes and is herein illustrated as embodied in a rounding and channeling machine of the type disclosed in 5 United States Letters Patent No. 600,883, granted March 22, 1898, upon an application of W. C. Meyer and Z. T. French. The invention is set forth hereinafter with particular reference to the rounding and channeling of soles which have been 10 applied to shoes in the process of repairing the shoes. The invention is not necessarily limited, however, in its application to repair work nor to machines for performing both rounding and channeling operations. Neither is the invention limited 15 to embodiment in machines of the particular type disclosed in the above-mentioned Letters Patent.

Machines of the type referred to are particularly designed for operation upon welt shoes and 20 are not ordinarily adapted for operation upon the soles of McKay-sewed shoes or other shoes of the type wherein the tread sole is directly secured to the upper, although a rounding and channeling machine fitted with mechanism adapting it for operation 25 upon the soles of both welt and McKay-sewed shoes is disclosed in United States Letters Patent No. 1,861,822, granted June 7, 1932, upon an application of O. L. Sherman and A. Bourgeois.

One object of the present invention is to provide, 30 in a machine for operating upon the soles of shoes, further improvements adapting the machine for operation not only upon the soles of welt shoes, but also upon the soles of shoes of the type wherein no welt or equivalent shoe bottom member is provided and wherein the tread sole is secured directly to the upper, as, for example, in McKay-sewed shoes, turn shoes, and shoes wherein the outsole is attached partially or wholly by 35 means of cement.

With this object in view, one feature of the invention consists in a machine for operating upon the soles of shoes of different types, comprising a movable feeding member or support for contact 40 with the work, a movable carrier, and a feeding device, belonging to a group of interchangeable feeding devices, arranged for mounting individually upon the carrier at the opposite side of a sole from the movable member and co-operating 45 with said member to feed the work, said feeding device being arranged for operation upon a type of shoe different from those upon which other devices of the group are to operate. In the rounding and channeling machine herein illustrated 50 provision has been made whereby two work-feed-

ing members or feed plates may be interchangeably attached to a feed plate carrier having the usual four-way feeding motion, thereby to adapt the machine for operation both upon the soles of welt shoes and upon the soles of McKay-sewed 5 shoes. Each feed plate, when attached to its carrier, is adapted to enter the crease between the upper and the margin of the sole and to cooperate with a sole support intermittently to grip the sole margin and to impart step-by-step feed 10 movements to the work. In resoling a welt shoe it is desirable to guide the shoe during the rounding and channeling of a new sole which has been temporarily secured to the shoe bottom by engagement with the edge of the welt which of 15 course has already been trimmed. To provide for the guiding of a welt shoe in this manner one of the interchangeable feed plates with which the present machine is provided has a welt edge gage rigidly secured thereto. In operating upon the 20 outsole of a McKay-sewed shoe, however, there is no welt from which the shoe may be guided and, accordingly, the other feed plate used in the present machine is equipped with a gage arranged to engage the upper of the shoe along an area 25 close to the sole margin to guide the shoe during the trimming and channeling of the outsole. To enable these two feed plates to be readily interchanged, clamping means is provided comprising a manually operable clamp bolt on the feed plate 30 carrier and an open slot in the feed plate so constructed and arranged that by a simple manipulation of the clamp bolt one of the feed plates may be removed and the other attached to the feed plate holder, the parts being assembled with the 35 end of the slot in the feed plate engaging the clamp bolt in such a manner as accurately to locate the feed plate in operative position in the machine.

In rounding and channeling machines as ordinarily constructed a work-supporting member, usually known as a crease guide, is provided for cooperating with the movable sole-feeding support to hold the work during those intervals when the feed plate has been retracted from feeding engagement with the sole margin. For a similar purpose the illustrated machine is provided with two normally stationary members, hereinafter more specifically referred to as presser feet, which are arranged for movement to different positions 50 to adapt them to act with one or another of a group of feeding devices belonging to an interchangeable group, each designed for use with a particular type of shoe. As herein disclosed, the presser feet may enter the crease between the 55

upper and the sole margins at opposite sides of the feed plate, to engage the upper face of the welt, in a welt shoe, or the upper face of the outsole margin, in a McKay-sewed shoe, to assist in supporting the portion of the work being operated upon. The feed plate for welt shoes supports the work so that the upper face of the welt is located in a different vertical plane from that occupied by the upper surface of the margin of the outsole of a McKay-sewed shoe when such a shoe is supported by the other feed plate. To adapt the presser feet of the illustrated machine properly to assist in supporting and gripping the work, the presser feet are made adjustable between two positions in one of which they are located for engagement with the face of the welt of a welt shoe and in the other of which they are located in a different vertical plane for engagement with the margin of an outsole of a McKay-sewed shoe. The illustrated presser feet, for this purpose, are secured upon a pivoted carrier which is adapted to be moved about its pivot by a manually operable eccentric adjusting device between two positions in one of which the presser feet are adapted to bear against the upper face of the welt of a welt shoe and in the other of which they are adapted to bear against the upper face of the projecting outsole margin of a McKay shoe. The provision, in a rounding or a rounding and channeling machine, of a presser foot adjustable as and for the purpose described constitutes another feature of the present invention.

The invention further consists in features of construction and combinations and arrangements of parts hereinafter described and claimed, the advantages of which will be apparent to those skilled in the art.

The invention will be explained with reference to the accompanying drawings, in which

Fig. 1 is a view in front elevation of so much of a rounding and channeling machine as is necessary to illustrate the application of the present invention thereto, the machine being shown as it appears when fitted and adjusted for operation upon a welt shoe, and certain parts of the machine being broken away for the purpose of better showing their construction;

Fig. 2 is a sectional view taken on the line II—II of Fig. 1;

Fig. 3 is an elevational view of the left-hand side of the machine, showing it in operation upon a welt shoe;

Fig. 4 is a fragmentary elevational view looking from the right-hand side of the machine and illustrating particularly the mounting of the presser foot;

Fig. 5 is a sectional view taken along the line V—V of Fig. 4;

Fig. 5a is a sectional view taken along the line X—X of Fig. 5;

Fig. 6 is a view similar to Fig. 3 but showing the machine in operation upon a McKay-sewed shoe;

Fig. 7 is a rear elevational view of the feed plate which is used for welt work;

Fig. 8 is a sectional view taken along the line VIII—VIII of Fig. 7;

Fig. 9 is a view partially in side elevation and partially in section of the feed plate for welt work;

Fig. 10 is a fragmentary front elevational view of the feed plate used for McKay work; and

Fig. 11 is a sectional view taken along the line XI—XI of Fig. 10.

Referring first to Figs. 1 and 3 of the drawings, the invention is therein shown as embodied in a rounding and channeling machine of the general

type disclosed in Letters Patent No. 600,883, hereinbefore referred to, the machine being provided with a four-motion feed plate 14 adapted to enter the welt crease of a welt shoe and to have feeding engagement with the upper surface of the welt, a sole support comprising an anti-friction roller 16 which is movable back and forth to cooperate with the feed plate 14 in feeding the work; a vibratory rounding knife 18 which is movable toward the feed plate to trim the outsole of the shoe; and a channeling knife 20 which is secured to the sole support. The sole support, the rounding knife and the channeling knife, above referred to, are substantially the same in construction and have substantially the same mode of operation as corresponding parts disclosed in said patent and, accordingly, no further description of these parts will be given herein. The machine is shown in Fig. 3 as operating to trim and form a stitch-receiving channel in a block outsole A which has been applied to a welt shoe, comprising an upper B and a welt C, in the process of repairing the shoe and temporarily secured to the shoe bottom by cement.

As best shown in Figs. 7, 8 and 9, the illustrated feed plate 14 is made in two parts consisting of an active portion 22, hereinafter referred to as the feed point, and a block or holder 24 to which the feed point 22 is fixedly secured. To adapt the illustrated machine for operation upon the soles of welt shoes, the feed point 22 has fixedly secured to its rear side a gage plate or welt edge gage 26 having a lower edge face 28 which is located above the lower extremity of the feed point 22 and is adapted for guiding a shoe by engagement with the previously trimmed edge of the welt. The edge 28 of the welt gage 26 is formed upon a block 30 of soft metal, which is dovetailed into the lower portion of the gage plate 26 to furnish a surface with which the rounding knife 18 cooperates in trimming a sole. The lower portion of the feed point holder 24 is notched or cut away, as indicated at 32 (Fig. 9), to receive the feed point 22 and the latter is positively located within the cut-away portion by means of two dowels 34, 34, which extend from the feed point holder into holes in the feed point. The welt gage 26 is secured to the feed point 22, and the feed point is secured to the holder or block 24, by means of a screw 36 the head of which is seated within the counterbored portion 38 of a recess in the holder and the shank of which extends through an aperture 40 in the feed point and is threaded into a clamp plate 42 which fits within a vertical slot 44 in the welt edge gage 26. A dowel 45 in the clamp plate 42 extends into one of the beforementioned dowel holes in the feed point 22 to assist in holding the clamp plate in place. The opposite lateral edges of the clamp plate 42 are beveled, as shown at 46 in Fig. 8, to overlie the corresponding beveled lateral edges of the slot 44 in the welt gage, the slot 44 being longer than the clamp plate 42. Consequently by loosening the screw 36 the welt gage 26 may be adjusted up or down relatively to the feed point to accommodate shoes having welts of different widths. The feed point holder or block 24 is, in turn, fixedly secured to a feed plate carrier 48 (Fig. 1) mounted for oscillatory and also lateral sliding movements upon a rod or bar 50 which is fixed at its opposite ends within frame members 52. The feed plate carrier 48 is caused to oscillate and to slide laterally upon the rod 50 to impart a four-way feeding motion to the feed

point 22 by means of cam mechanism which is not herein shown but which may be of the same construction as that of corresponding mechanism disclosed in Letters Patent No. 600,883 5 already referred to.

To adapt the machine for operation upon the soles of shoes in which no welt is employed, such for example as the McKay-sewed shoe D (Fig. 6) having the block outsole E applied thereto, a 10 second feed plate 56 is provided (see Figs. 6, 10 and 11). The feed plate 56 comprises a feed point 58 and a feed point block or holder 60 to which the feed point is rigidly secured, and a gage 62 is associated with the feed point 58 for 15 guiding a shoe by engagement with the shoe upper. As shown, the feed point holder 60 is identical in construction with the feed point holder 24 hereinbefore described, in order that the same pattern may be employed in the manufacture of 20 both holders, thereby reducing the cost.

The two feed points 22 and 58 may be used interchangeably in it to adapt the machine for operating upon both welt shoes and McKay-sewed shoes. For this purpose, each of the two 25 feed point blocks or holders 24 and 60 is provided in its upper portion with a vertical slot 64 which is open at its upper end to receive a clamp screw 66 on the feed plate carrier 48. In order to provide for the manual operation of 30 the screw 66 in a manner to permit instant removal or attachment of either feed plate, said screw is threaded within the feed plate carrier 48 and has fixedly secured to one end a handle 70 shaped to be conveniently grasped by the operator and by which the screw may be turned to cause the feed plate holder to be clamped between the head 72 and the side of the carrier 48. The pitch of the threads on the screw is preferably such that less than a full turn will be 35 sufficient to clamp or unclamp the feed plate. Each feed point holder is adapted to be located vertically in proper relation to the cooperating elements by engagement of the lower end of the slot 64 with the shank of the screw 66. A vertically elongated tongue or rib 74 on the carrier 48 extends into the slot 64 and into a groove 76 which constitutes an extension of the slot 64 at one side of the feed point holder to hold the latter firmly against angular displacement.

Referring now specifically to the feed plate 56, the gage 62 is located relatively to the feed point 58 to engage the upper of a shoe in a locality closely adjacent to the sole edge. It comprises a small roll having a periphery which 55 is slightly concave transversely to conform substantially to the contour of the shoe upper at that point, as shown in Fig. 6. The gage roll 62 is mounted upon the lower end of an arm 78 the upper portion of which is fitted within a shallow groove 80 in the feed point holder 60, the arm 78 being bent, as shown in Fig. 11, to support the roller in close proximity to the feed point. The arm 78 is rigidly secured to the feed point holder 60 by a screw 82 the shank of 60 which extends through a vertical slot 84 in the arm 78, through a hole 85 in the feed point holder 60, and is threaded into the feed point 58. As hereinbefore pointed out, the construction of the feed point holder 60 is the same as that of the holder 24 and, in order to provide for the firm 65 clamping in place of the arm 78, the counterbored portion of the hole 85 (which corresponds to the counterbore 38 in the holder 24) is filled by means of a collar 86. As shown, the gage 70 arm 78 is firmly held in place between the collar 75

86 and the head 88 of the screw 82 and edgewise displacement of the gage arm 78 is prevented by the sides of the groove 80. Angular displacement of the feed point 58 relatively to its holder 60 is prevented by means of dowels 90, 90 which extend from the feed point into the feed point holder. As shown, a cutting block 92 of soft metal is inserted in the lower portion of the feed point 58 for cooperation with the rounding knife 18. 5

In order that the cutting block 92 shall co-10 operate with the rounding knife 18 the feed point 58 is made thicker than the feed point 22, the thickness of the feed point 58 being equal to the combined thickness of the feed point 22 and the welt edge gage 26. Therefore when the feed point 15 58 is being used in the machine, the face of the cutting block 92 will be located in the same vertical plane as that occupied by the face of the cutting block 30 when the feed point 22 has been applied to the machine. 20

For the purpose of properly supporting the margin of a sole during those intervals when the four-motion feed point is retracted from feeding engagement with the sole, the present machine is provided with two stationary work supporting 25 members or presser feet 96 which are located one in front of and the other beyond the feed point so as to insure that the sole margin shall be adequately supported during the operating movement of the channeling knife. The presser feet 30 96 are shaped, as shown in Figs. 1, 3, 4 and 6, to enter the welt crease of a welt shoe (or the corresponding crease between the upper and the outsole of a McKay-sewed shoe), being formed for this purpose with beveled lower extremities 35 adapting them to extend substantially to the bottom of the crease and thus most effectively to support the sole margin. As shown, the angle of bevel of the work-engaging portions of the presser feet is somewhat steeper than that of 40 the corresponding portion of the feed point. As a result of this, they have no tendency to limit the extent of projection of the feed point into the crease and thus in no way to interfere with the effective feeding engagement of the feed point 45 with the work. The presser feet are located close to the feed point, they being separated by only sufficient space to provide the necessary clearance for its backward and forward movement. As illustrated, the presser feet 96, 96 are fixedly 50 secured by means of screws 98, 98 to a carrier arm 100 (best shown in Fig. 4) which, in turn, is mounted upon a bracket 102. The bracket 102 is conveniently hung upon the rod 59 and is formed with a rearwardly extending arm 104 55 which is rigidly secured by means of a bolt 106 to one of the frame members 52. The bolt extends through a hole 108 in the frame member which is somewhat larger than the diameter of said bolt so that ample provision is made for a 60 forward or backward setting-up adjustment of the presser feet in order that they may be accurately brought into the desired cooperative relation to the feed point. The screws 98, 98 extend through vertical slots 110, 110 (Fig. 1) in the 65 upper portions of the presser feet to permit up-and-down adjustment of the latter relatively to the carrier 100 so that the presser feet may be accurately positioned relatively to each other and to the feed point. 70

It is desirable that the work-engaging surfaces of the two presser feet shall bear the same relation to the work-engaging faces of the feed point whether the feed point 22 is employed to adapt the machine for operation upon welt work or the 75

feed point 58 for operation upon McKay work. Accordingly, provision is made for adjustment of the presser feet into two positions in one of which the presser feet will be adapted to support the sole margin of a welt shoe by engagement with the upper surface of the welt and in the other to engage the upper marginal surface of the projecting outsole of a McKay shoe. To this end, the carrier arm 100 to which the presser feet are secured is pivotally mounted in the bracket 102, as indicated at 112, and a rearward extension 114 of the carrier arms 100 is slotted, as shown at 116 (Fig. 4), to receive an eccentric portion 118 of an adjusting stud 120 rotatably mounted in the bracket arm 104. The stud is provided with a knurled collar 122 by which it may be turned to shift the presser feet between the positions shown in full and dotted lines. The presser feet are thus located in positions to engage, respectively, the upper face of a welt of a welt shoe and the upper surface of the margin of the outsole of a McKay shoe. The above-mentioned two positions of the presser feet are positively determined by the engagement of a sprung-pressed detent 124 carried by the arm 104 with one or the other of two notches 126, 128 in the adjusting stud 120. As shown, the detent 124 is shaped so that it will readily yield to release the adjusting stud 120 when the latter is turned but will nevertheless securely hold the stud in either of its two adjusted positions.

In using the illustrated machine for operating upon the soles of welt shoes the feed plate 24 with the welt gage 26 are employed and the presser feet 96 are adjusted into the position shown in Fig. 3 and in full lines in Fig. 4. In using the machine for operating upon the soles of McKay shoes, or other shoes in which no welts are provided, the feed plate 56 with the upper gage 62 are employed and the presser feet 96 are adjusted into the position shown in Fig. 6 and in dotted lines in Fig. 4. The feed plates are instantly interchangeable upon manipulation of the clamp screw 70 and adjustment of the presser feet is readily effected by a partial turn of the knob 122. The construction and mounting of the feed plates and of the presser feet are such that those parts are accurately positioned and rigidly supported at all times.

Having described my invention, what I claim as new and desire to secure by Letters Patent of the United States is:

1. In a machine for operating upon the soles of shoes of different types, a movable feeding member for contact with a sole, a movable carrier, and a feeding device belonging to a group of interchangeable feeding devices arranged for mounting individually upon the carrier at the opposite side of the sole from the movable member and cooperating with said member to feed the work, said feeding device being arranged for operation upon a type of shoe different from those upon which other devices of the group are to operate.

2. In a machine for operating upon the soles of shoes of different types, a movable feeding member for contact with a sole, a movable carrier, and a feeding device belonging to a group of interchangeable feeding devices arranged for mounting individually upon the carrier at the opposite side of the sole from the movable member and cooperating with said member to feed the work, said group including a feeding device having a gage portion arranged for contact with

the edge of a welt and another feeding device having a gage portion for contact with a shoe upper.

3. In a machine for operating upon the soles of shoes of different types, a sole trimming knife, a movable feeding member for contact with a sole, a movable carrier, and a feeding device belonging to a group of interchangeable feeding devices arranged for mounting individually upon the carrier at the opposite side of the sole from the movable member and cooperating with said member to feed the work, one feeding device of the group having a gage portion arranged for contact with the edge of a welt, such gage portion being provided with a surface against which the trimming knife acts and another feeding device of the group having a surface against which the trimming knife acts.

4. In a machine for operating upon the soles of welt shoes, in combination, a work support, a feed plate adapted to enter the crease between the welt and the upper of a welt shoe and to cooperate with said work support in feeding the work, a gage on said feed plate constructed and arranged to guide the work by engagement with the edge of the welt, a four-way motion carrier for said feed plate, a sole trimming knife arranged to cut against the face of the welt edge gage, and a manually operable clamp for detachably securing said feed plate to the carrier, said clamp being constructed and arranged to permit instant attachment and removal of said feed plate whereby a plurality of differently formed feed plates having different gages thereon may be interchangeably used in the machine to adapt the machine for operation upon different types of work.

5. In a machine for operating upon the soles of shoes, in combination, a work support, a work feeding device adapted to enter the crease between the upper and the projecting bottom margin of a shoe and to cooperate with said work support in feeding the work, a gage carried by said feeding device for guiding the work by engagement with the shoe upper, a movable carrier for said feeding device, mechanism for operating said carrier, and a manually operable clamp for detachably securing said feeding device to the carrier, said clamp being constructed and arranged to permit instant attachment and removal of said feeding device whereby a plurality of differently formed feeding devices having different work gages thereon may be interchangeably used in the machine to adapt the machine for operation upon different types of work.

6. For use in a machine for operating upon the soles of shoes, a feed plate adapted to enter the crease between a shoe upper and the projecting bottom margin of a sole and there having feeding engagement with said projecting bottom margin, there being an open-end slot in the feed plate, a quick-acting clamping device for effecting instant attachment or removal of the feed plate, and a work gage maintained in operating position in its relation to the feed plate for attachment and removal therewith.

7. For use in a machine for operating upon the soles of welt shoes, a feed point unit comprising a feed point holder having an open-end slot therein for cooperation with a quick-acting clamping device for locating and effecting instant attachment or removal of said holder, a feed point shaped to enter the crease between the upper and the welt of a shoe, and a welt edge gage secured to one side of said feed point.

8. For use in a machine for operating upon the soles of shoes having no welt or equivalent shoe

bottom member, a feed point unit comprising a feed point holder having an open-end slot therein for cooperation with a quick-acting device for locating and effecting instant attachment or removal of said holder, a feed point on said holder shaped to enter the crease between the upper and the projecting margin of a tread sole, and a gage secured to the holder and arranged to guide a shoe by engagement with the upper.

9. In a rounding and channeling machine, in combination, a work support, a four-way motion carrier, a feed point holder having an open-end slot therein, a clamp screw having a shank portion extending through said carrier and adapted to enter said slot, a head on the clamp screw adapted to clamp said holder to said carrier, interengaging means on said carrier and said holder for securing said holder against angular displacement, a manually operable member on said clamp screw, a feed point on said holder, a welt edge gage mounted upon said holder with provision for adjustment toward and from the operative extremity of the feed point, a clamp plate for securing said gage in adjusted position, and a screw securing said gage to said holder and holding said clamp plate in clamping position.

10. In a rounding and channeling machine, in combination, a work support, a four-way motion carrier, a feed point holder having an open-end slot therein, a clamp screw having a shank portion extending through said carrier and adapted to enter said slot, a head on the clamp screw adapted to clamp said holder to said carrier, interengaging means on said carrier and said holder for securing said holder against angular displacement, a manually operable member on said clamp bolt, a feed point on said holder, an upper gage on said holder, and means engageable with both the feed point and the gage for securing them to said holder.

11. In a machine for operating upon the soles of shoes, means for operating upon shoe soles, a movable feeding member, a feeding device belonging to a group of interchangeable feeding devices cooperating with said member, each feeding device of the group being arranged for individual cooperation with the feeding member, and a work support associated with the feeding device which is in use and being arranged for movement to different positions to adapt it to act with one or another of the group of feeding devices.

12. In a rounding and channeling machine, the combination with rounding and channeling means and a work support, of either of two interchangeable feed points of which one is adapted for use in feeding a welt shoe and the other for use in feeding a McKay-sewed shoe, and a presser foot capable of adjustment between two positions in one of which it is adapted to cooperate with one of said feed points and in the other of which it is adapted to cooperate with the other of said feed points.

13. In a rounding and channeling machine, in combination, a work support, a feed point adapted to cooperate with the work support in feeding the work, a work gage, a holder for the feed point and the work gage, a four-way motion carrier for said holder constructed and arranged to permit the use in the machine of either of two interchangeable holders each provided with a differently formed feed point and a differently formed and disposed gage for adapting the machine for operation upon different types of work, an adjustable presser foot for cooperating with

the work support in supporting the work, and means for adjusting the presser foot between two positions in one of which it is adapted to cooperate with the feed point of one of said holders and in the other of which it is adapted to cooperate with the feed point on the other of said holders.

14. In a machine for operating upon the soles of shoes, in combination, sole trimming means, a sole support, one of a plurality of interchangeable feed plates adapted for use in feeding different types of work, a four-way motion carrier adapted detachably to receive either of said feed plates, an adjustable presser foot for cooperating with the sole support in supporting the work, means for adjusting the presser foot into either of two positions in one of which it is adapted for use in cooperation with one of said feed plates and in the other of which it is adapted for use in cooperation with the other of said feed plates, and means for securing said presser foot in either of said positions of adjustment.

15. In a machine for operating upon the soles of shoes, in combination, means for supporting the work by engagement with the tread face of the outsole, a rounding knife for trimming the outsole, a carrier adapted detachably to receive either of two interchangeable feed devices and to position one with its work-engaging portion adapted for feeding engagement with the welt of a welt shoe and to position the other with its work-engaging portion in a different location for feeding engagement with the margin of an outsole for a McKay-sewed shoe, an adjustable presser foot for cooperating with said work-supporting means in supporting the work, and means for adjusting the presser foot between two positions in one of which it is cooperatively positioned with respect to the work-engaging portion of one of said feed devices and in the other of which it bears the same cooperative relation with respect to the work-engaging portion of the other of said feed devices.

16. In a machine for operating upon the soles of shoes, in combination, a sole rounding knife, a sole support, a feed plate for cooperating with said sole support in feeding the work, a presser foot for assisting in supporting the work, a pivotally mounted carrier for the presser foot, and means comprising a rotatable eccentric member for adjusting said carrier between two positions in one of which the presser foot is positioned for engagement with the welt of a welt shoe and in the other of which the presser foot is differently positioned for engagement with the margin of the outsole of a McKay-sewed shoe.

17. In a machine for operating upon the soles of shoes, in combination, a sole rounding knife, a sole support, a feed plate for cooperating with said sole support in feeding the work, a presser foot for assisting in supporting the work, a pivotally mounted carrier for the presser foot, means comprising a rotatable eccentric member for adjusting said carrier between two positions in one of which the presser foot is positioned for engagement with the welt of a welt shoe and in the other of which the presser foot is differently positioned for engagement with the margin of the outsole of a McKay-sewed shoe, and self-releasing latching means cooperating with said rotatable member for holding said carrier in either of said positions of adjustment.

18. In a rounding and channeling machine, the combination with the rounding and channeling means, of a sole support, a four-motion feed

5 point for cooperating with the sole support to feed the work, and two stationary presser feet adapted to enter the crease between the upper and sole margin of a shoe, said presser feet being arranged to engage the sole margin only at points in front of and beyond the area engaged by the feed point.

10 19. In a rounding and channeling machine, the combination with the rounding and channeling means, of a sole support, a four-motion feed point for cooperating with the sole support to feed the work, and two stationary presser feet adapted to enter the crease between the upper and sole margin of a shoe, said presser feet being arranged to engage the sole margin only at points in front of and beyond the area engaged by the feed point and said presser feet being adjustable toward and from the sole support between two positions in one of which the machine is adapted 15 for operation upon one type of work and in the other of which the machine is adapted for operation upon another type of work.

15 20. In a rounding and channeling machine, the combination with the rounding and channeling means, of a sole support, a four-motion feed point for cooperating with the sole support to feed the work, and two stationary presser feet

adapted to enter the crease between the upper and sole margin of a shoe, said presser feet being arranged to engage the sole margin only at points in front of and beyond the area engaged by the feed point and said presser feet being adjustable as a unit relatively to the feed plate in directions to vary the extent to which the presser feet extend into the crease between the upper and sole margin of a shoe being operated upon. 5

21. In a rounding and channeling machine, the combination with the rounding and channeling means, of a sole support, a four-motion feed point for cooperating with the sole support to feed the work, and two stationary presser feet adapted to enter the crease between the upper and sole margin of a shoe, said presser feet being arranged to engage the sole margin only at points in front of and beyond the area engaged by the feed point, said presser feet being adjustable as a unit relatively to the feed plate in 15 directions to vary the extent to which the presser feet extend into the crease between the upper and sole margin of a shoe being operated upon, and said presser feet being also independently adjustable in the aforesaid direction. 20 25
